UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK, A CORPORATION OF NEW YORK.

AUTOMATIC TRAIN-CONTROL SYSTEM.

Application filed September 1, 1920, Serial No. 407,302. Renewed December 30, 1924.

To all whom it may concern:

Be it known that I, CHARLES S. BUSHNELL, a citizen of the United States, residing at Rochester, in the county of Monroe 5 and State of New York, have invented certain new and useful Improvements in Automatic Train-Control Systems, of which the following is a specification.

This invention relates to automatic train control systems for railroads, and more particularly to an improved construction of the car-carried element of the impulse transmitting means by which the necessary controlling impulses or influences are transmitted 10 from the track to the moving car or other vehicle.

In one type of system to which my invention is more particularly applicable, the controlling impulses are transmitted by the 15 cooperation of a track element with a car-carried element, acting by electromagnetic induction through an intervening air gap; and the track element, when in its danger or stopping condition, is in effect a magnetic loop. It will be evident that in a system of this type, track rails at crossings, 20 crossovers and the like, or other masses of iron along the track, have a tendency to produce the same stopping effect as the regular track elements; and the primary object 25 of the present invention is to devise a car element of improved construction which will be influenced to a very slight degree by the track rails at crossings, crossover, and the 30 like, but which will be subject to the influence of a regular track element. Other more limited objects and features of the invention will appear hereinafter.

In describing the invention in detail reference will be made to the accompanying drawings in which—

Figure 1 shows diagrammatically one arrangement of trackway circuits and apparatus which may be employed in connection 45 with the car equipment embodying this invention;

Fig. 2, illustrates in a simplified and diagrammatic manner one form of car equipment constructed in accordance with the invention, together with the cooperating track element, the parts being shown more for the purpose of making it easy to understand the principles of the invention than with the idea of illustrating the exact construc-

tion and arrangement of parts which would 55 be preferably employed in practice;

Fig. 3 is a plan view of the car element; and

Fig. 4 is a fragmentary plan view of the car element showing a modified construction. 60

In the embodiment of the invention illustrated, the transmission of the desired controlling impulses is produced by track elements which are governed in accordance with 65 traffic conditions. Various arrangements of trackway circuits suitable for this purpose may be employed, and it should be understood that the arrangement shown in Fig. 1 is only typical. Referring to Fig. 1, the 70 track rails 1 of the railroad track are divided by insulated joints 2 into blocks in the usual way, one block I with the adjacent ends of two other blocks H and J being shown. The parts and circuits associated 75 with the various blocks are the same, and for convenience will be given like reference characters, with distinctive exponents. Each of the blocks is provided with a track battery 3 and a track relay 4, the same as 80 in ordinary block signal systems. My invention may be used with or without the usual fixed signals, depending upon the type of train control apparatus; and I have illustrated such fixed signals conventionally, 85 without attempting to illustrate their well known control circuits and devices.

The trackway element T of my invention in general comprises a magnetic yoke or core and associated coils, and is adapted to influence by electro-magnetic induction a co-operating element on a passing vehicle. In the construction illustrated, the trackway element T comprises a U-shaped core or yoke 5 provided with pole pieces 6, and having coils 7 on its legs which are wound and connected in series so that the electro-motive forces generated in these coils by flux passing through the yoke 5 are cumulative or additive. These trackway elements T 95 are intended to transmit controlling influences or impulses to a passing train at one or more control points in each block, in accordance with traffic conditions in the next block in advance alone, or both the next 100 block in advance and the corresponding block, depending upon the type of train control apparatus employed. In the track-

way equipment shown in Fig. 1, a trackway element T is located at the entrance to each block, a short distance in the rear of the insulated joints 2, the normal direction of traffic being from left to right, as indicated by the arrow. The coils 7 of each trackway element T are connected in series in a normally closed circuit including the front contact of a line relay 8. In the arrangement illustrated, the controlling circuit for the line relay 8 includes a front contact of the track relay 4 of the corresponding block and a front contact of the track relay 4 of the next block in advance, so that the coils 7 of the trackway element T at the entrance to each block are in closed circuit under clear traffic conditions, but are open-circuited when either the corresponding block or the next block in advance is occupied. The trackway elements T may be located crosswise of the track between the track rails (as shown in Fig. 1), or lengthwise, or outside of either track rail, as preferred.

The car element L for cooperating with the track elements T comprises a yoke or core Y having three vertically disposed legs 9, 10 and 11. This yoke Y is supported in a suitable manner (not shown) from the frame of the locomotive or other vehicle, and is so positioned on this vehicle that two of its legs, as 9 and 10, which are spaced apart the same distance as the legs of the track element T, will pass directly over the pole pieces of said track element, as shown in Fig. 2. On the middle leg 10 is a coil or winding 12, conveniently termed the primary coil; and on the other two legs 9 and 11 are similar coils 13 and 14, conveniently termed secondary coils. The secondary coils 13 and 14 are wound, preferably with the same number of turns, and are connected in series, such that the electro-motive forces generated therein by a change in flux passing through said legs in the same direction, either up or down, will oppose each other.

In connection with the system illustrated there is employed a device of the thermionic or vacuum bulb type, commonly known as an audion and conveniently referred to by that term. This audion, being well known in the art, is illustrated conventionally. It comprises a filament F, a grid G, and a plate P. This audion is connected up with suitable sources of current illustrated as batteries A, B and C, the primary and secondary coils of the car carried element L, and a control relay R, so that the operation of said relay R is automatically determined by the controlling condition of the track elements T as the vehicle successively passes them. It should be understood that these electrical connections may take various forms, the arrangement illustrated being merely typical.

The control relay R may be of any suitable type, but I prefer to employ a relay of a tractive type having its armature balanced about its center of gravity and biased to open by a spring; and in connection with the arrangement of circuits illustrated, I have found it desirable to use a relay having a large number of turns so as to be operable on small currents, and also having a laminated core so as to be quick acting. It will be evident, however, that the structural features of the relay R depend largely upon the type of audion employed, and other characteristics of the system. The control relay R is intended to control the operation of some suitable form of train control apparatus. Since this apparatus forms no part of the present invention, and may take any one of the various forms known in the art, I have illustrated conventionally such a device K in the form of an electro-pneumatic valve, which may be used to vent the train pipe and apply the brakes directly, or govern the operation of some other form of speed regulating or brake controlling mechanism. This train control device K is normally energized, and is deenergized when the control relay R opens its contacts. In the arrangement of circuits illustrated, the control relay opens its contacts only momentarily, so that if continued operation of the train control device K is desired, some suitable means, such as a stick circuit, should be employed all in the manner which will be readily understood by those skilled in the art.

The apparatus so far described constitutes the parts of a system which I have selected to illustrate the principles and mode of operation of my improved invention. This system is described and claimed in other applications.

In accordance with the present invention the two legs 9 and 11 carrying the secondary coils 13 and 14 are provided with pole pieces 15 and 16 which are elongated or extended lengthwise of the car. The pole pieces 15 and 16 may extend parallel with the track rails; or, as in the arrangement shown in Fig. 3, these pole pieces may be curved towards each other to form nearly a complete circle; or, as in the arrangement shown in Fig. 4, the end portions of these pole pieces 15^a and 16^a may be overlapped with an air gap between.

The circuit connections between the various devices are subject to considerable modification in practice, but in the particular arrangement illustrated, the filament F of the audion is heated by the battery A. The grid G is connected in circuit with the secondary coils 13 and 14 and the battery C as follows: commencing at positive terminal of battery C, wire 17, coil 13, wire 130

18, coil 14, wire 19, grid G, and thence to the filament F and back to the other terminal of the battery C. The plate P is connected in circuit with the relay R and the batteries B and C as follows: commencing at the positive terminal of the battery B, wires 20, and 21, relay R, wire 22, plate P, and thence through the audion to the filament F and battery C back to the other terminal of battery B. The primary coil 12 is normally energized by a circuit as follows: commencing at battery B, wires 20 and 23, train control device K, wire 24, contact finger 25 of relay R, wires 26 and 27, coil 12, wire 28, adjustable resistance 29, wire 30 and battery C back to the other terminal of the battery B. In order to protect the relay contacts from injury or deterioration by the arcs accompanying the breaking of the inductive circuit through the coil 12, a resistance 31 is preferably connected across these relay contacts.

Operation.—Normally the battery C produces a positive potential upon the grid G with respect to the negative end or average potential of the filament F, and thus permits current to flow in the plate circuit through the relay R, on account of the well known characteristics of the audion. The relay R being energized current flows through the primary coil 12 and produces magneto-motive force tending to send flux through the yoke 9. When the car is traveling between track elements T, this flux passes in part through the legs of the yoke 9 and in part through leakage paths. The reluctance of the partial magnetic circuit afforded by the yoke 9 is relatively high.

Assume now that the car passes over a track element T which has its coils 7 open-circuited, corresponding to dangerous traffic conditions ahead. A track element T is this condition presents in effect a dead magnetic loop for the two lefthand legs of the yoke 9 on the passing car, and it will be evident that as the car passes such magnetic loop, the reluctance of the partial magnetic circuit of the yoke 9 through the primary coil 12 and the secondary coil 13 is greatly changed, being decreased from the normal to a minimum and then back to normal as the car passes the track element. This change in reluctance in turn changes the amount of flux passing through the coils 12-13, the flux normally passing through the leakage paths being diverted to the path of lower reluctance through the iron of the yokes 9 and 5. As the flux through the coil 13 is increased, an electro-motive force is induced in said coil, which in accordance with well known laws, tends to produce a current making a magneto-motive force opposing this change of flux; and the windings are so arranged and connected that this induced electro-motive force opposes the voltage of the battery C and reduces the potential on the grid G. The normal potential on the grid G being thus lowered, the current normally flowing in the plate circuit through the control relay R is likewise decreased, and the parts are so proportioned and adjusted that the current through the relay R is reduced in this way below the value of current required to hold its contacts closed. Consequently, the contacts of the relay R open and deenergize the train control device K. Under clear traffic conditions, the coils 7 of the track element T are included in a closed circuit of low resistance; and when the car carried element L passes over a track element in this clear condition, the car equipment is not influenced, at least sufficiently to cause operation of the relay R. This is attributed to the action of the coils 7 which, it is believed, opposes or chokes back the passage of flux through the yoke 5 because of the current induced in said coils. It is found in practice that the number of turns on the coils 7, the length of the magnetic circuits, and the like, may be proportioned so that there is little change in the flux through the secondary coil 13 as it passes the track element T having its coils in closed circuit.

It will be evident that track rails or similar masses of iron along the track will tend to cause operation of the control relay R in the same way as a track element T in the danger or stopping condition; and to neutralize this objectionable interference, more particularly in the case of track rails, the additional leg and secondary coil 14 are employed. If both of the outer legs of the yoke Y pass over a magnetic body, as a track rail, substantially the same change in flux takes place through the coils 13 and 14; and since these coils are wound oppositely, the electro-motive forces induced therein are approximately balanced, so that the potential of the grid G is not lowered. It will be evident that an exact balance will be obtained if the track rail influences the secondary coils 13 and 14 simultaneously and to the same extent, so that equal and opposite voltages are induced in said coils. In practical working conditions, however, a track rail may sometimes be arranged at an angle to the track rails on which the car is traveling, as, for example, the points of a crossover. In such cases the track rail will approach or recede from the legs 9 and 10, before or after coming under the leg 11, with the result that the change of flux in the coils 13 and 14 does not take place simultaneously and to the same extent, thereby destroying the exact balancing or neutralizing action of the secondary coil 14. This is assuming that the legs 9, 10 and 11 have short or square pole pieces.

In accordance with the present invention, however, the elongated pole pieces 15 and 16 act as collectors for the legs 9 and 11, and cause a change of flux in both of the secondary coils 13 and 14 substantially simultaneously and to the same extent, as the car passes over an inclined rail. There are in effect two partial magnetic circuits in the car element L, one through the legs 9 and 10 and coils 12 and 13, and the other through the legs 10 and 11 and coils 12 and 14. In passing over a track element T, in the stopping condition, the partial magnetic circuit through coils 12 and 13 is completed through the yoke 5 of said track element and the intervening air-gaps, while the other magnetic circuit through the secondary coil 14 is not materially affected. In passing over an inclined track rail, both magnetic circuits are affected through the elongated pole pieces 15 and 16; and although the length of the path through the iron of these pole pieces may not be the same, the change in reluctance of said partial magnetic circuits is practically the same. In this connection, it should be remembered that the pole pieces of the yoke Y are separated from the track rails by an air gap which must be at least an inch or two, on account of the clearances demanded by practical railroad conditions. Such an air gap provides, therefore, the greater part of the reluctance of the magnetic circuit through the yoke Y and the track rail; and consequently the effect of some additional iron path through the elongated pole pieces 15 and 16 is practically negligible.

The arrangement of elongated pole pieces does not seriously detract from the effect produced by an active track element T. I attribute this to the fact that a track element produces its maximum influence while passing directly under the legs 9 and 10, and at such time said track element is not in position to affect the neutralizing secondary coil 14 directly, or through its elongated pole piece 16.

While I have described my invention in connection with a system of the specific type embodying an audion, the invention is not limited to this type of system and I desire to have it understood that the specific embodiment of my invention, shown and described is merely illustrative, and does not exhaust the adaptations and modifications of means and functions thereof constituting the invention.

What I claim as new and desire to secure by Letters Patent of the United States is:—

1. In a system of automatic train control of the type in which controlling impulses are transmitted from the track to moving cars through an intervening air gap by the cooperation of a car element with a track element which acts as a magnetic body when

in the stopping condition, a car element comprising a three-legged yoke, two of said legs having elongated pole pieces, oppositely wound coils on said two legs, and electro-responsive means having an operating circuit connected to said coils in series. 70

2. In an automatic train control system of the type specified in claim 1, a car element comprising a source of magneto-motive-force, two oppositely wound coils in circuit therewith, electro-responsive means having an operating circuit including said coils in series, and magnetic members extending in a horizontal plane and acting as collectors for said coils. 80

3. In an automatic train control system of the type specified in claim 1, a car element arranged to provide two magnetic circuits, a source of magneto-motive-force for said magnetic circuits, means operated when the reluctance of only one but not both of said circuits is changed, and magnetic members extending horizontally and acting as collectors for said circuits. 85

4. In an automatic train control system of the type specified in claim 1, a car element comprising a three-legged yoke, the outside legs of said yoke having horizontally disposed pole pieces curving toward each other, and means operated when the reluctance of the magnetic circuit through one of the outside legs is changed. 95

5. A car element for automatic train control systems comprising a yoke having three legs, the two outside legs having elongated pole pieces curving toward each other and acting as collectors. 100

6. A car element for automatic train control systems comprising a three-legged yoke provided with coils and having elongated pole pieces on the outside legs curved toward each other in the same plane. 105

7. A car-carried train control apparatus comprising, a three-legged yoke, two of said legs having horizontally extended pole pieces, oppositely wound coils on said two legs connected to the grid circuit of a thermionic amplifier, and train control mechanism controlled by said amplifier. 110

8. A car-carried train control mechanism comprising, a three-legged yoke, two of said legs having elongated pole pieces, oppositely wound coils on said two legs for governing a thermionic amplifier, and train control means controlled by said amplifier. 115

9. A car-carried impulse device for automatic train control systems comprising, a plurality of partial magnetic circuits, and means associated with said magnetic circuits for changing the reluctance of each of said circuits simultaneously when said device passes over a bar of magnetic material of sufficient length to span said device, disposed at any angle to the direction of the motion. 125

10. A car-carried element for automatic train control systems comprising a yoke with two legs, each of said legs terminating in horizontally disposed elongated pole pieces 5 curved toward each other and adapted to be bridged by an elongated member on the track at substantially any angle with respect to the legs.
11. A car-carried element for automatic train control systems comprising, a three-legged yoke, two of said legs terminating in pole pieces extending horizontally substantially around the third leg.
12. A car-carried element for automatic train control systems comprising, a three-legged yoke, two of said legs terminating in pole pieces magnetically separated and substantially surrounding the other leg.
13. In a train control system, a car-carried influence receiving element comprising, two windings, a source of magneto-motive force for said windings, and horizontally extended magnetic members associated with said windings and cooperating with a rail 25 at substantially any angle to the running rails to direct flux simultaneously through both windings during movement of the element over such rail, and a track element adapted when in the stopping condition to 30 direct flux from said source through one of said windings only.
14. In a train control system, a car-carried influence receiving element comprising, two windings and a core for said windings having pole pieces extended to come simultaneously over a rail at substantially any angle to the running rails during movement of the element over such rail.
15. In a train control system, the combination with a non-magnetized track element extending partway across the track between the rails, a car-carried receiving element comprising two partial magnetic circuits, said track element acting to complete one of said magnetic circuits but not the other, the car-carried element having horizontally extended magnetic members adapted to cooperate with a rail at substantially any angle to the track rails and form 50 a path for flux through both of said magnetic circuits during its movement over such rail.
16. In a train control system, the combination with a car-carried element having a core with three legs, one of said legs having a pole piece extending horizontally far enough to come over a rail at any angle at the time said rail comes under one of the other legs, and a track element of magnetic material bridging the other two legs only.
17. In a train control system, the combination with a track element comprising, a U-shaped magnetic core, and a car-carried element having three legs, two of said legs
- passing over the ends of the core of the track element, the third leg having a pole piece extending horizontally far enough to come over a rail at any angle to the track way at the time said rail comes under one 70 of the other legs.
18. In a train control system, the combination with a car-carried three-legged yoke disposed crosswise of the car and having horizontal pole pieces extended for a 75 substantial distance lengthwise of the car, and a track element including a U-shaped magnetic core bridging two legs only on said yoke.
19. In a train control system, the combination with a car-carried influence receiving element comprising, two partial magnetic circuits and a source of magneto-motive force in each circuit, electro-responsive means operated by a changing of 80 flux in one of said circuits, said means not responding to simultaneous change of flux in both of said circuits, said car element having horizontally extended magnetic members arranged to cooperate with a rail 85 at substantially any angle to the track rails and to simultaneously change flux in both of said magnetic circuits as the element passes such rail, and a track element for causing a change of flux in one of said magnetic circuits but not the other.
20. A car-carried influence receiving element comprising, a three-legged yoke disposed crosswise of the car, two legs of said yoke having horizontally extended pole 90 pieces arranged to be both over a track rail at substantially any angle to the running rails during movement of the third leg over said track rail.
21. A car-carried influence receiving element comprising, a core having three legs, two of said legs having pole pieces extended horizontally on opposite sides of the third leg.
22. In a train control system, the combination with a car-carried element comprising, a core having three legs, two of said legs having horizontally extended pole pieces, and a track element bridging only one of said two legs and the third leg.
23. A car-carried influence receiving element for cooperation with a track element having a non-magnetized U-shaped core, comprising two partial magnetic circuits, each terminating in elongated pole pieces extended horizontally lengthwise of the car.
24. A car-carried influence element for automatic train control system, comprising a primary coil, two oppositely wound secondary coils connected in series, electro-responsive means governed by potential changes in said secondary coils, and magnetic members extended horizontally lengthwise of the car and arranged to form a path for flux from the primary coil through both

secondary coils simultaneously during movement of the car over a rail disposed at substantially any angle to the car.

25. A car-carried element for train control system, comprising a primary coil and a core therefor, said core extending cross-wise of the car, and horizontally disposed elongated pole pieces extended forwardly and rearwardly with respect to the car.

10 26. A car-carried element for train control system comprising, a core extending transversely of the car and having three downwardly extending legs, two of the legs having arcuate pole pieces disposed substantially in the same horizontal plane and substantially surrounding the third leg but magnetically separated.

20 27. In a train control system, train control mechanism on a vehicle, an influence receiving element on the vehicle including a primary coil, an energizing circuit for the coil controlling said train control mechanism, electro-responsive means for governing the operation of the train control mechanism, oppositely wound secondary coils connected in series for governing the electro-responsive means, and elongated pole pieces associated with secondary coils and disposed horizontally on opposite sides of the primary coil.

28. A car-carried influence receiving element for train control systems, and electro-responsive means associated therewith, said electro-responsive means being operated when said car-carried element cooperates with a track element constituting a partial magnetic circuit when in the active stopping condition, said car element being provided with horizontally disposed magnetic members extended lengthwise of the vehicle and adapted to be bridged by a track rail at substantially any angle.

29. A car-carried element for train control systems, comprising a three-legged yoke, a primary coil on one leg, oppositely wound secondary coils connected in series on the other two legs, said other two legs having extended pole pieces adapted to be bridged by a rail at substantially any angle to the track rail as it comes opposite the leg on which the primary coil is carried.

30. A car element for automatic train control systems comprising, a three-legged yoke having two of its legs provided with pole pieces extending in a horizontal plane with their ends overlapped and surrounding the third leg.

In testimony whereof I have affixed my signature.

CHARLES S. BUSHNELL.
